UNITED STATES PATENT OFFICE

FRENCH E. DENNISON, OF BELOIT, WISCONSIN, ASSIGNOR TO NATIONAL REFRIGERATION CORPORATION, OF BELOIT, WISCONSIN, A CORPORATION OF DELAWARE

REFRIGERATING APPARATUS

Application filed July 26, 1928. Serial No. 295,424.

This invention relates to refrigeration apparatuses:

In the use of refrigerating apparatuses in general, compactness is highly desirable as well as an arrangement whereby a maximum of heat transference may be obtained between the compressed refrigerant and the cooling fluid therefor, with a minimum of loss by radiation.

10 The primary object of this invention is accordingly to provide a refrigerating apparatus which has a large refrigerative capacity while occupying a minimum of space.

Another object of this invention is to provide a refrigerating apparatus in which a maximum of heat transference takes place between the compressed refrigerant and the cooling fluid.

Another object of this invention is to provide a refrigerating apparatus having a condenser for the refrigerant which is readily accessible for inspection, renewal and repair.

A further object of this invention is to provide a refrigerating apparatus, in which the cooling water is circulated in proximity to the condenser at a rate of flow which will be unfavorable to the depositing of sediment and scale.

30 Other and further objects of this invention will be apparent as the same becomes better understood from an examination of the specification and claims in connection with the accompanying drawing wherein is shown a refrigerating apparatus embodying this invention.

Referring to the drawing more particularly, reference character 1 designates a horizontally elongated hollow casting open 40 at one end which forms a base for the apparatus and a housing for the condenser and refrigerant receiver, as will be hereinafter explained.

The casting 1 is provided with integral 45 legs 2 at its lower side and at its upper side with integral raised supports 3 for a motor 4, integral raised supports 5 for a control box 6 for the motor 4, and integral raised supports 7 for a compressor 8 connected to 50 said motor.

A helical condensing coil 9 is longitudinally disposed in the casting 1, the convolutions of said coil being loosely seated in a helical groove 11, formed in the inner periphery of the casting 1, the groove being substantially as deep as the diameter of the pipe forming the coil so that the convolutions of the coil are separated from each other by the groove walls forming in effect a spiral rib 12 extending inwardly from the wall of the casting 1.

One end 13 of the coil 9 extends coaxially of the coil and casting 1 through a suitable aperture 14 located centrally of the closed end 15 of said casting, said closed casting end being provided with a gland 16 surrounding said coil end for sealing said closed end at said aperture. The end 13 is detachably coupled to the delivery end of a valve 17. This valve 17 is connected at its intake 18 by means of a pipe connection 19 to the discharge of the compressor 8. The opposite end 19 of the coil 9 extends through a central aperture 21 in a removable closure plate or head 22 removably bolted to the open end of the casting 1. The head 22 is provided with a gland 23 surrounding the end 19 of the coil for sealing the head at the aperture 21. The end 19 of the coil is detachably coupled to an elbow 20 leading to a valve 24. The valve 24 is supported by and is adapted to deliver refrigerant through a pipe 25 which extends back through the head 22.

A cylindrical casing 26 closed at one end is fused at its open end to the interior of the head 22, and is adapted to receive compressed and cooled refrigerant from the pipe 25. This casing 26 together with the inner face of the head 22 forms the refrigerant receiver and extends longitudinally of the casting 1 through the coil 9. The outer periphery of the casing 26 extends in close proximity to the inner periphery of the rib 12 whereby the circulating water, which is admitted through a pipe 27 extending through the head 22 and is discharged through a pipe 28 extending through the closed end of the casting 1, will be compelled to flow substantially within the

groove 11 in close proximity to the individual convolutions of the coil 9. The circulating water being thus confined to the groove 11 will develop considerable velocity and will not only prevent the accumulation of sediment and scale on the outer walls of the coil, but since it travels in close proximity to the coils and against the direction of the flow within said coils, it will cause a maximum of heat transference between the refrigerant within the coils and the water.

The refrigerant receiver being at all times within the casting 1 in contact with the cooling water, a further cooling of the compressed refrigerant may be obtained after the same is admitted to the receiver, and in addition, the apparatus is rendered more compact, requiring a minimum of space.

The head 22 is also provided with a fitting 29, including a suitable valve in communication with the interior of the refrigerant receiver and adapted to deliver the refrigerant to the evaporator (not shown). After the refrigerant has been used in the evaporator it is returned to the compressor through pipe 30.

By merely removing the coupling (not shown) by means of which the fitting 29 is connected to the evaporator line, detaching the coupling connecting the end 13 of the condensing coil with the valve 17, removing the connection to the circulating supply line, and removing the head bolts, said coil and the refrigerant receiver may be screwed out for inspection, renewal or repair as a unit. By merely uncoupling the fitting 29 from the evaporator line, the pipe 27 from the circulating water line and the end 19 of the coil from the elbow 20 and removing the head bolts the refrigerant receiver may be withdrawn horizontally from said casting 1. The coil 9 may then be screwed out alone.

In assembly, the coil 9 is introduced into the casting 1 from the open end thereof and is advanced horizontally to its position by threading it into the helical groove 11.

The advantages as to compactness and efficiency of heat transference with a minimum of loss by radiation and the operation of the apparatus will be apparent from the foregoing without further description.

I am aware that many changes may be made without departing from the principles of this invention and I therefore do not wish to be limited to the details shown or described.

I claim:

1. In a refrigerating apparatus, the combination of a housing, and a condensing coil the convolutions of which are threadedly engaged with said housing.
2. In a refrigerating apparatus, the combination of a housing, and a condensing coil removably connected with the housing, the

convolutions of the coil being in threaded engagement therewith.

3. In a refrigerating apparatus, the combination of a housing provided with a circulating chamber, a condensing coil disposed in said chamber, means for circulating cooling fluid through said chamber longitudinally of the coil including channels for causing substantially all of the fluid to flow along the individual convolutions of the coil in close proximity thereto and a refrigerant receiver connected to the discharge end of the coil with its walls forming part of the walls of said channel.

4. In a refrigerating apparatus, the combination of a generally cylindrical hollow housing, a helical condensing coil disposed in said housing with its convolutions in proximity to the walls of said housing, the latter being provided with a groove to receive the convolutions of the coil, and a member presenting a cylindrical surface cooperating with said groove to form therewith a helical passage for the circulating fluid and to enclose the convolutions of said coil.

5. In a refrigerating apparatus, the combination of a generally cylindrical hollow housing, a helical condensing coil disposed in said housing with its convolutions in proximity to the walls of the housing, the latter being provided with a groove to receive the convolutions of the coil, and a refrigerant receiver presenting a cylindrical surface cooperating with said groove to form therewith a helical passage for the circulating fluid and to enclose the convolutions of said coil.

6. In a refrigerating apparatus, the combination of a housing, a condensing coil the convolutions of which are threadedly engaged with said housing, and a refrigerant receiver surrounded by said coil.

7. In a refrigerating apparatus, the combination of a housing having a helical groove on its interior surface, a helical condensing coil with its convolutions disposed in said groove, and a cylindrical member disposed inside of said coil forming with said groove a helical channel surrounding the convolutions of the coil, and connections for circulating a cooling fluid through said channel.

8. In a refrigerating apparatus, the combination of a housing having a helical groove on its interior surface, a helical condensing coil the convolutions of which are disposed in said groove and which is removable therefrom by an unscrewing movement, and a cylindrical member disposed inside of said coil forming with said groove a helical channel surrounding the convolutions of the coil, and connections for circulating a cooling fluid through said channel.

In witness of the foregoing I affix my signature.

FRENCH E. DENNISON. 130
